(57) **CLAIM**

The ornamental design for a fan, as shown and described.

DESCRIPTION

FIG. 1 is a front side elevation view of a fan.

FIG. 2 is a rear side elevation view.

FIG. 3 is a right side elevation view.

FIG. 4 is a left side elevation view.

FIG. 5 is a top plan view.

FIG. 6 is a bottom plan view.

FIG. 7 is a front side elevation view for reference.

FIG. 8 is a cross sectional view taken along 8—8 line in FIG. 3, omitting the lead wires.

FIG. 9 is a cross sectional view taken along 9—9 line in FIG. 3, omitting the interior mechanism of a motor.

FIG. 10 is a cross sectional view as taken along 10—10 line in FIG. 7, omitting the interior mechanism of a motor.

FIG. 11 is a cross sectional view as taken along 11—11 line in FIG. 7, omitting the interior mechanism of a motor; and, FIG. 12 is a perspective view for reference.

The broken lines throughout the drawing figures are included for the purpose of illustrating portions of the fan that form no part of the claimed design.
